UNITED STATES PATENT OFFICE.

CHARLES E. WHITE, OF CHICAGO, ILLINOIS, ASSIGNOR TO FRANK B. COOK, OF CHICAGO, ILLINOIS.

ELECTRICAL PROTECTIVE DEVICE.

No. 838,066.

Specification of Letters Patent.

Patented Dec. 11, 1906.

Application filed January 9, 1905. Serial No. 240,320.

To all whom it may concern:

Be it known that I, CHARLES E. WHITE, a citizen of the United States, residing at Chicago, in the county of Cook and State of Illinois, have invented certain new and useful Improvements in Electrical Protective Devices, of which the following is a specification.

This invention relates to electrical protective devices, and refers particularly to those that are self-restoring—that is to say, which resume a normal position after the line has been opened and which may be used over and over again indefinitely.

In its present embodiment the invention refers to such a protector in which the heat generated during the passage of a sneak or other unusually heavy current over the circuit expands the air within a closed chamber, the expansion of the air moving a diaphragm to operate a mechanical device to break the circuit. The protector is automatically restored to a normal position when the temperature of the air within its closed chamber falls below the temperature at which the protector is arranged to operate.

In the accompanying drawings, Figure 1 is a perspective view of one embodiment of my invention, portions of the circuit in which the protector is included being also shown. Fig. 2 is a horizontal section through the protector and its supporting means. Fig. 3 is a longitudinal section through the resistance-coils and their supporting means. Fig. 4 is an end view of the parts shown in the last preceding figure. Fig. 5 is a diagrammatic view illustrating one of my protectors included in a circuit to be protected, also showing diagrammatically a signaling-circuit adapted to be opened and closed by the protector. Fig. 6 is a diagram showing several protectors included in such a signaling-circuit.

In the drawings I have illustrated this protector in connection with the distributing-board 1 of a telephone-exchange, said board in this instance being formed of an upright piece of angle-iron provided with a base-flange 2.

3 refers to the cable containing the line-wires, 4 to the cable of switchboard-wires, 5 to the usual ground connection for the distributing-board, and 6 and 7 to the line-terminals. Though these line-terminals are exactly alike, still for ease in tracing the cir-

cuits said terminals will be distinguished each from the other. Each comprises a screw-threaded rod 8 8^a, insulated from the distributing-board 1 by means of the two-part insulating-bushings 9 9^a. Upon the opposite ends of the rods 8 8^a are binding-nuts 10 10^a and 11 11^a, and between the nut 10 10^a and the bushing 9 9^a upon each of said rods is mounted a finger 12 12^a. At its upper end the finger 12 12^a carries a carbon block 13 13^a, forming a part of a lightning-arrester, and at its lower end it is connected with the line-wire 14 14^a. The other carbon block 15 15^a of the lightning-arrester is secured to and electrically connected with the distributing-board 1 by a clip 16 16^a. By means of two nuts 17 17^a a spring contact-finger 18 18^a is mounted upon each of the screw-threaded rods 8 8^a about midway of the length of said rods. A projecting contact-point 19 19^a upon said finger is adapted to engage the clip 16 16^a, but is normally held out of engagement with said clip by a detent means to be described later herein. An angular bracket 20 extends the length of the distributing-board 1, one flange of said bracket being secured to said board by means of the rods 8 8^a and the other flange being provided with a series of countersunk openings 21, only one of which openings is shown in the drawings. In each of these openings is secured, in any suitable manner, the body portion of a bell-shape air-cartridge 22. The large end or mouth of said cartridge is closed by means of a thin metallic diaphragm 23, having a centrally-placed stud 24 fixed to its outer side.

The tubular stem 25 of the air-cartridge is closed at its outer end and is adapted to be surrounded by a metallic sleeve 26. Two resistance-coils 27 and 28 are fixed upon said sleeve in any suitable way. A supporting-spider 29, of insulating material, is secured upon the sleeve 26 adjacent to the bracket 20 and carries at the ends of its four arms four contact-points 30, 31, 32, and 33. The ends of the wire forming the coil 27 are attached to the contact-points 31 and 32, while the ends of the wire of the coil 28 are attached to the contact-points 30 and 33. A contact-finger 34 34^a is secured upon the end of the rod 8 8^a adjacent to the bracket 20 by means of the nut 11 11^a; but said finger is insulated from said rod by an insulating-bushing 35 35^a. Each of the contact-fingers 34

34^a is connected, by means of a wire 36 36^a, with one of two terminals 37 on the distributing-board 1 for the line running to the switchboard. Only one of said terminals is shown in the drawings. In the diagram Fig. 5 the numeral 38 refers to said switchboard. Contact-fingers 39 and 40 are secured to the bracket 20, one end of each of said springs contacting the contact-points 32 and 33 of the spider 29. The opposite ends of said springs are bent and cross one another, at the point of crossing being secured to the stud 24 upon the diaphragm 23, but being insulated from each other and from said stud. Beyond said point of crossing the ends of the springs 39 and 40 are bent to form hooks 41 and 42 for holding the free ends of the contact-fingers 18 18^a out of contact with the clips 16 16^a. The free ends of said contact-fingers and the ends of the hooks 41 and 42 are beveled, so that said fingers may be readily pushed into engagement with said hooks in closing the circuit after the protector has operated.

In order to provide means for informing the line superintendent or other person in charge of the lines of the exchange that the protector has operated, I arrange a circuit common to a plurality of protectors, said circuit consisting of wires 43 and 44, battery 45, bell 46, and light 47, as shown in Fig. 5. The terminals 48 and 49 of the wires 43 and 44 are suitably supported adjacent to the free ends of the contact-springs 39 and 40, so that when said springs are moved by the diaphragm 23 they shall contact said terminals, and thus close the signal-circuit just described. As shown in Fig. 6, any number of protectors may be included in the same signal-circuit.

The circuit guarded by the protector may be traced as follows: line 14, finger 12, screw-threaded rod 8, finger 18, spring-finger 40, contact-point 33, resistance-coil 28, contact-point 30, contact-finger 34, wire 36, switchboard 38, wire 36^a, spring-finger 34^a, contact-point 31, resistance-coil 27, contact-point 32, spring-finger 39, contact-finger 18^a, screw-threaded rod 8^a, line 14^a. The signal-circuit may be traced as follows: battery 45, wire 43, light 47, bell 46, terminal 49, contact-spring 39, contact-point 32, resistance-coil 27, contact-point 31, finger 34^a, wire 36^a, switchboard 38, wire 36, finger 34, contact-point 30, resistance-coil 28, contact-point 33, spring-finger 40, terminal 48, line 44 to battery 45.

When a current of abnormal strength enters the working circuit, its passage through the coils 27 and 28 generates sufficient heat to expand the air confined within the air-cartridge 22. The expansion of the air moves the diaphragm 23 and the spring-fingers 39 and 40. Being thus released the contact-fingers 18 18^a spring into contact with the clips 16 16^a, grounding the working circuit.

The movement of the spring-fingers 39 and 40 also brought them into contact with the terminals 48 49 of the signaling-circuit, closing said circuit and actuating the signals 46 and 47. When the temperature of the air in the air-cartridge 22 falls below the temperature at which the protector is arranged to operate, the diaphragm resumes its normal position, opening the signaling-circuit. The working circuit may now be restored to operative condition by manually moving the contact-fingers 18 18^a into engagement with the hooks 41 42.

Two resistance-coils are provided in order to prevent a sneak-current upon the line from reaching the switchboard or a heavy current causing a short circuit upon the switchboard from reaching the instruments on the line. Should the resistance-coils 27 28 be damaged, they may be removed, together with their supporting sleeve and spider, by rotating said spider to move the ends of its arms out from under the ends of the springs 34 34^a 39 40 and a new sleeve, spider, and set of coils substituted for the injured set.

It is clear that my improved protector may be used in other connections than that herein shown and that the construction and arrangement of parts shown and described may be modified in various ways without departing from the spirit and scope of my invention. I therefore would have it understood that I do not wish to limit myself to the precise embodiment illustrated, but desire to claim the invention broadly.

I claim as my invention—

1. In an electrical protective device, in combination, two circuit-openers adapted to be included at different points in a circuit; a detent for each of said circuit-openers; and a single means for simultaneously operating said detents, said detent-operating means comprising a separate actuating means included in each side of the circuit.

2. In an electrical protective device, in combination, a circuit-opener; a detent for said circuit-opener; means for operating said detent comprising an air-chamber having a diaphragm; and a resistance-coil in circuit with said circuit-opener, said coil surrounding a portion of said air-chamber.

3. In an electrical protective device, in combination, a circuit-opener; and means for operating said circuit-opener, comprising a bell-shape air-chamber, a diaphragm for closing the large end of said chamber, and a resistance-coil surrounding the smaller end of said chamber.

4. In an electrical protective device, in combination, two ground connections; two spring contact members each adapted to complete a circuit through one of said ground connections; two detent-springs, one for each of said contact members, said detent-

springs forming parts of the circuit and being arranged to move together; an air-chamber having a diaphragm; a connection between said diaphragm and said detent-springs for moving said detent-springs; and a resistance in circuit adapted to heat the air in said air-chamber.

5. In an electrical protective device, in combination, a circuit-opening device; and means for operating said device comprising an air-chamber and a resistance member removably mounted upon a portion of said chamber.

6. In an electrical protective device, in combination, a circuit-opening device; and means for operating said device comprising an air-chamber and a resistance-coil, said coil being mounted upon a sleeve adapted to surround a portion of said chamber and to 20 be removably held with relation thereto.

7. In an electrical protective device, in combination, a circuit-opening device; and means for operating said device comprising a bell-shape air-chamber and a resistance-coil, which coil is mounted upon a sleeve adapted to surround the smaller end of said air-chamber and to be removably held with relation thereto.

8. In an electrical protective device, in combination, two members adapted to be included in different sides of a circuit; means for moving said members to break said circuit, comprising an air-chamber and two resistances for heating the air in said chamber, 35 each of said resistances being connected to one of said members.

9. In an electrical protective device, in combination, two members adapted to be included in different sides of the circuit; means 40 for moving said members to open said circuit, comprising an air-chamber and two resistance-coils for heating the air in said chamber; a device carrying said coils and adapted to be removably secured in operative relation 45 to said air-chamber; and means for connecting each of said coils to one of said members.

10. In an electrical protective device, in combination, two members adapted to be included in different sides of the circuit and being mechanically connected together; and means for simultaneously moving said members to break said circuit, comprising an air-chamber, a diaphragm for said air-chamber connected to said circuit members, and two 55 resistances for heating the air in said chamber, each of said resistances being connected to one of said members.

11. In an electrical protective device, in combination, a supporting member; two 60 members forming part of the circuit and adapted to lie in contact with each other; means for separating said members comprising an air-chamber supported by said supporting member, and a resistance-coil mounted upon a sleeve adapted to surround a por-

tion of said air-chamber, said sleeve having a securing projection thereon electrically connected with said coil, means for securing said projection to said supporting member, and means for electrically connecting said projection with one of said circuit members. 70

12. In an electrical protective device, in combination, a circuit-opening device; a support therefor; an air-chamber supported by said support; a heating device adapted to 75 heat the air in said chamber; a member secured with relation to said heating device; and an engaging device mounted upon said support and adapted to engage the member fixed with relation to the heating device, for 80 supporting said heating device in operative position.

13. In an electrical protective device, in combination, a support; circuit members carried by said support for forming parts of the 85 two sides of a circuit; means for moving certain of said members to break each side of said circuit, comprising an air-chamber carried by said support; two resistance-coils; a sleeve for supporting said coils; a spider fixed 90 to said sleeve; terminals on said spider for said coils; and engaging means on said support electrically connected with said circuit members and adapted to engage said terminals for holding said sleeve in position. 95

14. In a protector-board or similar structure, in combination, a board comprising two flanges extending at an angle with each other; two line-terminals mounted on one of said flanges; two switchboard-terminals 100 mounted on the other of said flanges, each of said line-terminals being electrically connected with one of said switchboard-terminals; and a single means for breaking the electrical connection between each of said pairs of terminals. 105

15. In a protector-board or similar structure, in combination, a board comprising two flanges extending at an angle with each other; a switchboard-terminal mounted upon one of 110 said flanges; a line-terminal mounted upon the other of said flanges; a bracket secured to one of said flanges and supporting a portion of the circuit; and means supported by said bracket for opening the circuit upon the passage of an abnormal current. 115

16. In a protector-board or similar structure, in combination, a supporting structure carrying line-terminals and switchboard-terminals; an angular bracket supported by said structure and carrying circuit members electrically connected with said terminals and adapted to contact with each other; and means for separating said circuit members supported by said bracket. 120
